Wm L. Sanderson Assignor to
S. Cole & G. C. Mosher of Troy, N. Y.
Letters Patent. No. 311. Dated August 27, 1850.

The Schedule referred to in these Letters Patent and making part of the same.

To all to whom these presents shall come:

Be it Known that I, Wm L. Sanderson of Troy, in the County of Rensselaer, and State of New York, have invented or produced a new and original design of ornamental coal stove for heating purposes, and I do hereby declare that the following is a full and exact description of the same, reference being had to the annexed drawings, which make a part of this specification, in which fig. 1. is a view of a side plate, fig. 2. of the top, fig. 3. of the bottom plates, and fig. 4. a view of the Mica frame.

The front, back & side plates are all of the same pattern of ornament as represented in fig. 1. the back plate having a pipe hole and the front a door. The ornaments consists of arabesque, scroll figures &c as represented, the top and bottom plates are ornamented with arabesque figures, as represented in the drawings.

2

Des. 3/1

One half of the ornament of the plates are not represented, it being the same as that represented reversed on the blank half of the plate.

The mica frame (fig. 4) secures the mica in the openings A A in the front and sides.

Having thus described my design what I claim as new and desire to secure by Letters Patent is the design and configuration of ornamented stove plates, substantially the same as herein described and represented.
